Primary Examiner — Antoine D Davis(74) *Attorney, Agent, or Firm* — Kilpatrick Townsend & Stockton LLP(57) **CLAIM**

The ornamental design for a cone and debris screen for a rain gauge, as shown and described.

DESCRIPTION

FIG. 1 is a top perspective view of a cone and debris screen for a rain gauge showing my new design;

FIG. 2 is a front elevational view thereof;

FIG. 3 is a side elevational view thereof;

FIG. 4 is a top plan view thereof;

FIG. 5 is a bottom plan view thereof; and,

FIG. 6 is a cross-sectional side view thereof.

The submitted line drawings (FIGS. 1-6) show some additional solid lines on the cone and debris screen for a rain gauge; some of these solid lines are not meant to convey actual solidly drawn lines, such as actual surface markings or ornamentation. As is generally recognized by persons skilled in the art of preparing digital drawings, such solid lines are meant to convey the boundaries for curved surfaces on the device.

The broken lines showing on the drawing disclosure is for illustrative purposes only and form no part of the claimed design.
